UNITED STATES PATENT OFFICE.

WALTER W. WEISER, OF CHICAGO, ILLINOIS.

PIANO.

Application filed October 10, 1924. Serial No. 742,775.

To all whom it may concern:

Be it known that I, WALTER W. WEISER, a citizen of the United States, residing at Chicago, in the county of Cook, State of Illinois, having invented certain new and useful Improvements in Pianos, do hereby declare that the following is a full, clear, and exact description of the same.

My invention relates to pianos, and its object is to provide new and improved organizations whereby adjustments of the string-plate to govern the bearing of the strings on the bridge may be made from the top and without removing any of the parts from the case or even disassembling them. With this advantageous object or result in view, the invention consists in the novel and useful constructions herein described and then pointed out in the appended claims.

In the accompanying drawings, which illustrate a practical embodiment of my invention and in which the same reference numerals indicate the same or similar parts in the different views, Fig. 1 is a top plan view of the frame, sounding-board and string-plate assembled together and equipped with my invention;

Fig. 2 is a detail sectional view on the line 2—2 in Fig. 1 on an enlarged scale, and showing also a portion of the frame and back of the case;

Fig. 3 is a detail sectional view on the line 3—3 in Fig. 2;

Fig. 4 is a detail sectional view on an enlarged scale showing an alternative form of screw;

Fig. 5 is a detail sectional view on an enlarged scale taken on the line 5—5 in Fig. 1, and

Fig. 6 is a detail sectional view on an enlarged scale taken on the line 6—6 in Fig. 1.

Within the case indicated generally by the reference numeral 1 is mounted the usual frame 2, which carries the sounding-board 3 and the string-plate 4; the piano actions are of usual type and are not shown in the drawings. The shape of the frame 2 is determined by the scale according to variation in the length of the strings and is approximately as shown in Fig. 1 for grand pianos; it is usually provided with a center post 5. The string-plate 4 is shaped in general to conform to the shape of the sounding board; it is provided with strengthening ribs 6 and carries the hitch-pins 7 and tuning-pins 8

for the strings 9, and suitable openings are provided in the plate as at 10 and 11 above the sounding-board bridges 12 and 13, respectively, for the treble and overstrung scale and the bass scale. The sounding-board 3 preferably does not extend entirely to the front of the plate 4, but terminates sufficiently short thereof as shown in Fig. 1 to leave a free space at the front below the plate.

In pianos as constructed prior to my invention the string-plate was spaced above the sounding-board by interposed blocks, and screws or bolts were inserted through the plate and passed through the spacing-blocks and the sounding-board into the frame. In time the sounding-board sinks more or less, and in order to set the plate down to get the same bearing of the strings on the bridge as when the piano was new it was necessary to remove the screws and spacing blocks and to substitute new blocks of appropriate size. This necessitated not only the disassembling of the string-plate, sounding-board and spacer-blocks, but also the removal of this entire unit from the case in order to disassemble these parts and then re-assemble the unit with new blocks. The job consumed time and was expensive, and generally required the shipment of the piano to and from the factory.

These objections and disadvantages are obviated by my invention, which enables the string-plate to be adjusted with relation to the sounding-board to govern the pressure of the strings on the bridges without removing any parts, and the entire operation can be performed by a simple turning or wrench instrument, such as a screw-driver, wrench, turning-key or spanner, according to the form of the heads of the spacer-screws and holding-screws employed.

In the embodiment of my invention shown in Figs. 1, 2 and 3 the spacing elements are headed screws 14 which pass through the sounding-board 3 and are adjustably seated in the frame 2 with their heads in position to support the plate 4 at suitable distance above the sounding-board, the plate being provided with passages or openings 15 in register with the screws but of less diameter than their heads and through which a screw-driver can be entered to turn the screws. The holding or pressure screws 16 are long enough to pass through the plate 4 and

sounding-board 3 into the frame 2 and their heads hold the plate on the spacing screws. In the form shown in Fig. 6, the spacing elements are square-headed screws 17 adjustably seated in the frame 2 with their heads supporting the under surface of the plate 4 at suitable distance above the frame, and the same holding-screws 16 are here also employed. This form is preferably employed at the front of the unit as shown in Fig. 1; the open space below the front of the plate 4 afforded by the relative shortness of the sounding-board allows the operator room to turn the heads 18 of the screws 17, and by this arrangement these screws are concealed beneath the plate 4 and out of sight when the cover is raised.

In the form shown in Fig. 4 the spacing elements are square-headed screws 17 adjustably seated in the frame 2 and having intermediate collars or bosses 19 beneath and supporting the plate 4; the heads 18 of these screws pass freely through openings 20 in the plate 4 so that they can be turned by a wrench. In this form the holding or pressure screw 16 is preferably square-headed as at 18 so that the same turning instrument can turn it; it is provided with an intermediate collar or boss 16^a which bears on the plate 4.

All the forms above described are especially suitable for use at the margins of the unit, although they could conveniently be used at the intermediate adjustment point indicated at the section line 5—5 in Fig. 1. However, I prefer to provide a simpler form for this location, which consists of a combined spacer and pressure member. As shown in Fig. 5, the screw 21 is adjustably seated in the center-post 5 of the frame and is provided with a square portion 22 to receive the turning wrench; its head extends freely through an opening 23 in the sounding-board 3 and is provided with an upper shoulder 25 to support the string-plate 4. The upper end of the head is reduced and screw-threaded to receive a nut 26 which holds the plate 4 upon the shoulder 25 and is provided with a screw-driver nick 27.

In the embodiment of my invention the spacer elements are adjustably seated in the frame to form abutments for the string-plate 4 on opposite sides of the bridges, and

the holding or pressure elements clamp this plate upon the spacers. When it is desired to adjust the bearing or pressure of the strings on the bridge the spacer elements are appropriately adjusted in the frame 2, and the pressure or holding elements are set down to hold the plate 4 in proper position on the spacers with relation to the sounding-board. All the parts are permanently mounted in the piano, and all of the adjustments and operations to raise and lower the plate to decrease or increase the pressure or bearing of the strings on the bridge to bring out the tone can be accomplished while the parts are assembled in the unit in the case and without disassembling or removing any part, and they can be made with any ordinary suitable turning instrument. Also, in all the forms shown, except that of Fig. 5, the adjustments can be made from the top of the piano. In short, a piano-tuner during his usual work of tuning the strings can perform all the operations necessary to adjust or govern the pressure of the strings on the bridge that heretofore required the disassembly of the parts and substitution of new spacers. Various modifications can be made in the form of the spacing and pressure elements without departing from the scope of my invention.

I claim:

1. In a piano, a frame, a sounding-board and a string-plate supported on the frame, spacing-screws adjustably mounted in the frame and having heads supporting the plate in spaced relation to the board, said plate having openings in line with said screws, and holding-screws mounted in the frame and clamping the plate on the spacing-screws.

2. In a piano, a frame, a sounding-board and a string-plate supported on the frame, spacing-members adjustably mounted in the front and rear portions of the frame adjacent to and supporting the plate in spaced relation to the board, holding-members clamping the plate on the spacing-members, and a combined spacer and pressure member adjustably seated in the frame intermediate the sounding-board bridges.

In testimony whereof I hereto affix my signature.

WALTER W. WEISER.
